LOUNGE

Charles Eames, Venice, Calif., assignor to Herman Miller,
Inc., Zeeland, Mich., a corporation of Michigan

Filed Mar. 3, 1969, Ser. No. 16,006

Term of patent 14 years

Int. Cl. D6—01

U.S. Cl. D15—11

FIG. 1.

FIG. 2.

FIG. 3.

FIG. 4.

FIG. 1 is a perspective view of a lounge showing my new design:

FIG. 2 is a front perspective view of the lounge illustrated in FIG. 1;

FIG. 3 is an end elevational view of the lounge illustrated in FIGS. 1 and 2; and

FIG. 4 is an end elevational view of the end of the lounge illustrated in FIGS. 1 and 2 opposite from the view shown in FIG. 3.

I claim:

The ornamental design for a lounge, substantially as shown and described.
